US00D730315S

(12) **United States Design Patent**
Stevinson

(10) **Patent No.:** **US D730,315 S**
(45) **Date of Patent:** **** May 26, 2015**

(54) **EARPHONE CADDY**

(71) Applicant: **Dean Stevenson**, Centennial, CO (US)

(72) Inventor: **Dean Stevenson**, Centennial, CO (US)

(**) Term: **14 Years**

(21) Appl. No.: **29/445,405**

(22) Filed: **Feb. 11, 2013**

(51) LOC (10) Cl. **14-01**

(52) U.S. Cl.

USPC **D14/205; D3/201**

(58) **Field of Classification Search**

USPC D14/205, 204, 201, 251–252, 144, 243;
D3/201, 203.1, 218, 269; 206/45.24,
206/216, 314, 305, 320, 457, 701;
455/569.1, 575.1–575.8; 381/74

(57) **CLAIM**

The ornamental design for an earphone caddy, as shown and described.

DESCRIPTION

FIG. 1 is a rear perspective view of a first embodiment of the earphone caddy;

FIG. 2 is a front perspective view of the first embodiment of the earphone caddy;

FIG. 3 is a top plan view of the first embodiment of the earphone caddy;

FIG. 4 is a bottom plan view of the first embodiment of the earphone caddy;

FIG. 5 is a right side elevation of the first embodiment of the earphone caddy;

FIG. 6 is a left side elevation of the first embodiment of the earphone caddy;

FIG. 7 is a rear elevation of the first embodiment of the earphone caddy;

FIG. 8 is a front elevation of the first embodiment of the earphone caddy;

FIG. 9 is a rear perspective view of a second embodiment of the earphone caddy;

FIG. 10 is a front perspective view of the second embodiment of the earphone caddy;

FIG. 11 is a top plan view of the second embodiment of the earphone caddy;

FIG. 12 is a bottom plan view of the second embodiment of the earphone caddy;

FIG. 13 is a right side elevation of the second embodiment of the earphone caddy;

FIG. 14 is a left side elevation of the second embodiment of the earphone caddy;

FIG. 15 is a rear elevation of the second embodiment of the earphone caddy; and,

FIG. 16 is a front elevation of the second embodiment of the earphone caddy.
